FLUID PUMP

Gunnar A. Wahlmark, Rockford, Ill.

Application June 8, 1938, Serial No. 212,475

10 Claims. (Cl. 103—42)

The invention relates more particularly to a unitary pump and the valve device for supplying fluid under pressure to oil burners.

It is a general object of the invention to provide a new and improved fuel pumping and control unit of this character.

Another object is to provide a fuel pumping unit embodying the pumping elements so arranged that by removing a cover portion of the casing the pumping elements may be removed and replaced without disturbing pipe connections or the driving connection to the pump motor, and more particularly to provide such a unit with either single stage or two-stage pumping elements.

Another object is to provide such a fuel pump with pumping elements assembled in a unitary device so that they may be secured together and removed as a unit.

Another object is to provide a fuel pumping unit with a drive shaft extending from one end and a removable cover on the other, and strainer and pumping elements withdrawable when the cover is removed without disturbing the drive shaft and its seal mechanism.

Further objects include the provisions of a pumping unit permitting change of the pumping elements without disturbing the pipe connections, drive shaft, mechanical seal or drive motor, and in which single and two-stage pump assemblies are interchangeable and readily located in the housing.

Other objects will become readily apparent from the following detailed description taken in connection with the accompanying drawings, in which:

Fig. 1 is a plan view of a preferred form of the invention.

Fig. 2 is an elevation looking at the left hand end of Fig. 1.

Fig. 3 is a vertical central section substantially along the line 3—3 of Fig. 1.

Figs. 4, 5 and 6 are sections respectively along the lines 4—4, 5—5, and 6—6 of Fig. 3.

Fig. 7 is a vertical central section through another form of the invention.

Figs. 8 to 11 are sections respectively along the lines 8—8 to 11—11 of Fig. 7.

Fig. 12 is a section along the line 12—12 of Fig. 3.

While I have shown in the drawings and shall herein describe in detail a preferred embodiment of my invention, together with a modification thereof, it is to be understood that I do not intend to limit the invention to the specific forms dis-

closed but aim to cover all modifications and alternative constructions falling within the spirit and scope of the invention as expressed in the appended claims.

In the forms chosen for purposes of disclosure, the invention comprises generally a two-part casing 20, 20', a pumping device or means 21, a drive shaft 22, a mechanical seal 23 for the drive shaft, a strainer 24, and a control valve mechanism 25. It is contemplated that the shaft 22 will be connected by suitable means to a driving motor (not shown), that an inlet port 26 will be connected to a source of fluid supply, and a discharge port 27 to a burner nozzle. The casing parts are formed to provide a substantially cylindrical chamber or recess 28 in which the pumping device 21 and strainer 24 are positioned for purposes hereinafter more fully described.

As illustrated herein, the casing part 20 is in the form of a body member which is also used for supporting the fuel unit. Preferably this member is formed with supporting lugs 29 having bolt receiving apertures 30 (Fig. 4). The part 20' is in the form of a closure or cover and is bolted to the part 20 by means of a plurality of screw devices 31. Thus, if the unit is mounted with the surface 29' of the lugs against a suitable bracket or other support, a suitable motor may be connected to the shaft 22 and the necessary pipe connections made to the ports in the casing part 20 to provide a permanent installation. As hereinafter more fully described, the internal parts of the unit may thereafter be removed for inspection, repair or replacement without disturbing the driving motor or pipe connections, merely by removing the cover part 20'.

In the form illustrated in Figs. 1 to 6 and 12, the pumping device 21 comprises a toothed roller or drive element 32, an internally toothed element or ring 33, a crescent guard member 34, 40 and a housing for these elements consisting of circular members or end plates 35 and 36 and an intermediate annular member 37. The housing parts form a cylindrical pump chamber and are preferably secured together by means of a pair of screw devices 38 so that the pumping device may be pre-assembled as a unit before insertion into the casing chamber 28. The guard member 34 is secured to the plate 36 by pins 34'. The unit is secured in the casing against the end wall 28' of the cylindrical chamber 28 by means of the plurality of screw devices 39 (Fig. 3) which extend through the end plates 35 and 36 and the intermediate member 37 and into threaded engagement with the casing part 20. In order

to facilitate locating the pumping unit in the casing, it is preferably provided with a pair of pins 40 and corresponding bores 41 in the part 20 for receiving the pins. The adjacent end of 5 the drive shaft 22 extends into the chamber 28 and has a key-way 22' into which a key 42 on the roller 32 fits in driving relation when the pumping unit is secured in place.

Fluid is admitted to the casing chamber 28 by 10 means of the inlet port 26 (Fig. 1) and passes through the strainer 24 before entering a pump inlet port 45 (Fig. 6) formed in the pump housing end plate 35. The strainer, as illustrated in the drawings, is made of suitable gauze and 15 is cup-shaped, a channel-like ring 46 secured to the peripheral edge of the strainer being arranged to fit snugly over the outer surface of the end plate 36 of the pumping unit and up against the adjacent end wall 28' of the chamber 20. The strainer may be reenforced by means of a wire helix 24'.

After passing the pumping elements 32, 33, the fluid is discharged into an outlet recess 50 in the end plate 36 (Fig. 5) and through a port 51 (Figs. 25 4 and 5) which is formed in the casing part 20 and communicates with a valve chamber 52.

The valve mechanism designated generally as 30 25 is operable to control the discharge of fluid from the pumping unit and preferably functions only after the discharge pressure has attained a predetermined value. Should the discharge pressure exceed the predetermined value due to an obstruction in the discharge pipe or nozzle or for any other reason the valve mechanism is 35 arranged to by-pass a portion of the fluid either to the source of supply or the casing chamber 28.

In the forms of the invention illustrated herein, the casing part 20 has a depending portion 53 provided with a transversely extending bore 54 (Fig. 4). The valve chamber 52 is formed in this bore between the adjacent ends of a bushing 55, which is screw-threaded into one end of the bore 54, and a sleeve member 56 which is pressed into the central portion of the bore 54. The 40 bushing 55 contains the discharge port 27 which is formed in part by the hole in a leather or composition washer 57 secured in a recess in the inner end of the bushing 55. A hollow piston valve 58 is slidably mounted in the sleeve 56 so that the operative end 57' thereof will be subjected to the fluid in the valve chamber 52. This valve is held seated against the washer 57 to close the discharge port 27 by means of a coiled spring 59 which is positioned within the hollow 45 piston valve. A cap member 60 screw-threaded in the other end of the bore 54 carries a screw device 61, the free end of which engages in a cup-shaped member 62 seated against the adjacent end of a coil spring 59 to provide for adjusting the pressure of the spring on the piston valve and thereby the fluid pressure at which the valve opens. Preferably, a removable closure 63 is threaded on the cap 60 so as to protect the adjusting device 61 and facilitate access thereto 55 to permit inserting a screw driver to turn the screw device.

In order to by-pass excess fluid, the piston valve 58 is also arranged to uncover a by-pass port 65 which is formed in the sleeve 56 and 70 communicates with an annular passage 66 formed around the sleeve 56 (Figs. 3 and 4). This annular passage communicates with a vertically extending port by-pass 67 (Fig. 3) which in turn communicates at its upper end with the casing 75 chamber 28 to provide an internal by-pass, and

communicates at its lower end with the exterior of the casing to provide an external by-pass. If the fuel unit is to be installed in what is generally referred to as a single pipe system, this internal by-pass is utilized for the excess fluid, and the 5 lower end 67' of the port 67 is closed by means of a suitable plug 167" as shown in Fig. 3. If, however, the fuel unit is to be used in a two-pipe system, a suitable plug 167' is placed in the upper threaded portion 67' of the port 67 as shown in 10 Fig. 7, and the outer end 67" of the port is connected to the return pipe.

In order to insure quiet operation of the pump, means is provided for completely filling the fluid conveying recesses in the roller and ring as they 15 pass the crescent 34, at which time the fluid in the recesses is not under pressure. As illustrated in the drawings, this means includes a port 70 (Figs. 3 and 5) in the end plate 36, the port communicating with an arcuate chamber 71 in the 20 end plate. The port 70 is located so as to communicate with the fluid carrying recesses 33' (Fig. 12) of the ring element as they pass over the guard 34. A recess 70' in the end plate 35 is positioned opposite the port 70 and communicates with the recesses 33' and also with recesses 32' in the roller 32 as they pass the guard 34, so that the recesses in the roller as well as those in the ring will be filled, if necessary. A thin wall or disk member 72 separates the arcuate chamber 30 71 from an opposed arcuate chamber 73 (Figs. 3 and 4) formed in the casing part 20. This arcuate chamber communicates at its lower end with a passage 74 which connects with the annular passage 66. The wall 72 is preferably made of 35 impregnated fabric or other suitable material so that the outer portions thereof may serve as a sealing gasket between the end plate 36 of the pump device and the end wall 28' of the chamber 28, and is provided with an overflow opening 75 40 above the level of the port 70 so that fluid from the arcuate chamber 73 may overflow into the arcuate chamber 71 and maintain the port 70 and recess 70' filled.

In operation, the fuel unit of Figs. 1 to 5 is 45 arranged to function automatically when driven at the proper speed. When the pump is started, the piston valve 58 closes the discharge port 27 and is not operated to open said port until the pressure in the valve chamber 52 reaches a pre- 50 determined amount. Normally, the arcuate chamber 71 remains filled with fluid with the result that this fluid feeds through the port 70 to the passing recesses in the ring 33 and through recess 70' to the roller recesses 32. Thus, if any 55 of these recesses are not completely filled with fluid, they are filled as they pass the port 70. Normally, these recesses are filled as they pass the inlet port 45 when the shaft 22 is rotated in a counterclockwise direction as viewed from 60 the right hand end of Fig. 3. Preferably, an arcuate cavity 45' is formed in the plate 36 (Fig. 5) opposite the inlet port so as to facilitate the filling of the recesses in the pump elements. Fluid from the discharge port 50 of the pump passes 65 downwardly through the passage 51 to the valve chamber 52 and builds up pressure in said chamber until it is sufficient to operate the valve. It will be readily apparent that as soon as the pressure is sufficient, the piston valve slides to- 70 ward the left as shown in Fig. 4 and opens the discharge port 37. Should the pressure in chamber 52 rise still further, the piston valve slides sufficiently far to the left to uncover the by-pass port 65 and passes any excess fluid into the an- 75

nular passage 66 and from there into the by-pass port 67 and also into the passage 74 and chamber 73. If the upper end 67' of the by-pass port 67 is unblocked and the lower end 67 is plugged (as shown in Fig. 3), the by-passed fluid passes directly into the chamber 28.

Preferably, the piston valve 58 is provided with an annular recess 58' and a connecting side wall port 58'' so as to relieve any pressure which may build up in the left hand end of the bore 54 and thus insure proper operation of the valve. Likewise, a leakage return port 80 is provided in the casing part 20 so as to supply fluid to a chamber 81 in which the mechanical seal 23 is located. A port 82 (Figs. 1 and 3) is provided in the upper portion of the casing part 20 for the reception of a vacuum gauge and a port 83 (Fig. 2) is provided in the portion 53 for the reception of a pressure gauge, the port 83 communicating at its inner end with the valve chamber 52.

The form of the invention illustrated in Figs. 7 to 11 is in many respects identical with that of Figs. 1 to 6 and 12, the differences residing wholly in the construction of the pumping unit and the strainer. The pumping unit of this form is a two-stage device and will now be described in detail.

This pumping unit comprises end plates 35 and 36, an intermediate plate 85 and annular spacing members 86 and 87. A first stage pump comprising a roller 88 and an intermeshing toothed ring 89 are operable in the chamber formed intermediate the plates 35 and 85, and a second stage pump comprising a roller 90 and a toothed ring 100 operate in the chamber formed intermediate the plates 85 and 36. The rollers 88 and 90 are provided with driving pins 101 and 102 respectively which interengage with a keyway 103 in a drive shaft 104 when the pumping unit is assembled.

A crescent 105 for the first stage pump is suitably secured to the plate 85, and a crescent 106 is secured to the end plate 36 for the second stage pump.

In this form of the invention, the end plate 35 (Figs. 7 and 11) contains an inlet port 45 for supplying fluid to the first stage pump, the intermediate plate 85 having an opposed arcuate cavity 45' (Fig. 10). A discharge port 110 for this pump is formed in the intermediate plate 85 (Fig. 10) and extends upwardly to connect with a port 111 which extends through the member 87 and plate 36 so as to discharge into an annular recess 112 in the end plate 36. The second stage pump is provided with fluid from this recess through an inlet port 113 (Fig. 9) formed in the end plate 36. Fluid discharged from the second stage pump passes through an outlet port 114 in the plate 36 and thence through a discharge port 115 in the end plate and a connecting port 116 in the casing (Fig. 8) which communicates with the valve chamber 52.

The elements forming the first stage pump have a wider face as indicated in Fig. 7, so that an excess of fluid will be supplied to the second stage pump. The excess is permitted to overflow through the opening 75 in the partition wall 72 from whence it may pass downwardly through the passage 74 and annular passage 66 and into the vertical by-pass port 67. The parts 86, 85 and 87 of the two-stage pump are preferably located one on the other, and on the mounting plate 36 by means of pins 40' which are aligned with the pins 40. The pins 40' extend part-way into the member 86, all the way through members 85 and

87, and part-way into the holes in plate 36 in which the pins 40 are partly inserted.

A cup-shaped strainer 120 is provided in this form of the invention to surround the pumping unit. Preferably, the strainer has an outer side wall 121 and an inner side wall 122 joined by means of a channel-like annular member 123 which is spaced from the surrounding casing and pump parts, as shown in Fig. 7 so as to permit fluid to flow therebetween and pass through the inner wall 122. The inner wall 122 is also provided with a channel-like annular member 124 which fits snugly around the plate 35 to provide a support for the strainer. The fluid supply pipe connected to the casing 20 discharges into the casing chamber 28 in the same manner as illustrated in Figs. 1 to 6 so that the fluid must pass through the strainer before being admitted to the first stage pump.

In the form of the invention embodying the two-stage pump, fluid also enters the recess 28 by means of an intake port 26 as shown in Figs. 1 and 2. The fluid passing to the first stage inlet 45 passes through the strainer on its way. The first stage pump generally serves as a suction pump for drawing fluid through the intake pipe to the chamber 28, through the strainer and into the inlet 45. The output from the first stage pump passes through the ports 110 and 111 (Figs. 10 and 11) and into the arcuate recess 112 (Fig. 30 9) from whence it passes to the inlet port 113 for the second stage pump. The excess fluid from the first stage pump passes out through the overflow opening 75 and through arcuate recess 73, passage 74, recess 66 and into the by-pass port 67. The fluid discharged by the second stage pump passes through ports 114, 115 and 116 to the valve chamber 52. The valve functions to control the discharge of fluid through the port 27 and the bypass of fluid to the port 67 and chamber 73 in the same manner as set forth for the single stage unit of Figs. 1 to 6 and 12.

The casing of the unit is preferably built as shown to accommodate either a single stage pump or a two-stage pump. In this manner, the number of different parts used in constructing the two pumps is maintained at a minimum, the parts of the two-stage unit being identical with those of the single stage unit with the exception of the two-stage pump, the strainer, and the screws for securing the two-stage pump in the casing. In fact, parts of the two-stage pump are identical with those of the single stage pump, as, for example, the end plate 35 and the pumping elements of the first stage. As shown herein, the same drive shaft is used for the two forms of the invention, the end plate 35 of the single stage unit being centrally apertured to permit the use of the longer shaft of the two-stage unit, as illustrated in Fig. 3.

The preferred construction also provides for convenient replacement of the pumping means (or change of the unit from single to two-stage or vice versa) without disturbing the drive motor, the drive shaft or the mechanical seal, and also without disturbing the pipe connections. Thus, as will be readily apparent from Figs. 3 and 7, it is merely necessary to remove the closure 20' whereupon the strainer may be pulled out. Thereafter, by removing the bolts 39 (or 39'), the pumping means in each case may be removed as a unit by pulling it off the end of the drive shaft. This facilitates removal of the pumping units for cleaning and repairing or for replacement. It is also possible to remove the 75

valve mechanism without disturbing the pipe connections by unscrewing the cap member 60 and withdrawing the valve out toward the left, as shown in Figs. 4 and 8.

5 The preferred construction is such that the pump assemblies are readily interchangeable and are easily located by the pins 40.

10 The mechanical seal 23 in the particular form shown herein is the subject matter of a copending application Serial No. 179,168, filed December 10, 1937.

I claim as my invention:

15 1. A device of the character described comprising, in combination, a casing having a cylindrical recess in one end thereof, a shaft receiving bore extending through the other end thereof and a depending portion having a transversely extending bore for housing valve mechanism, a detachable closure for the recessed end of the 20 casing, a drive shaft rotatably mounted in said shaft receiving bore having one end extending into said cylindrical recess and the other end projecting from the casing, a rotary pumping means positioned in said cylindrical recess and driven by said shaft and including a circular 25 plate mounting member detachably secured to the end wall of said recess, an intake port in said casing communicating with said cylindrical recess, an inlet port for the pumping means communicating with said cylindrical recess, an arcuate recess in said circular plate member in the 30 face engaging the casing which communicates with said pumping means, an arcuate recess in the adjacent wall of the casing, means separating said recesses and having an aperture connecting upper portions of said recesses to provide an overflow opening, an outlet port for the 35 pumping means connected to said valve housing bore, a bypass port from said valve housing bore back to said cylindrical recess, a port connecting the lower portion of the second arcuate recess with said bypass port, a discharge port, and valve means in said valve housing bore for controlling the flow of fluid through said bypass and discharge ports.

40 45 50 55 60 65 70 75 2. A device of the character described comprising, in combination, a casing having a cylindrical recess therein, a rotary pumping means positioned in said cylindrical recess, including a circular mounting member detachably secured to one end wall of said recess, an intake port in said casing communicating with said cylindrical recess, an arcuate recess in said circular mounting member in the face engaging the casing which communicates with said pumping means, an arcuate recess in the adjacent wall of the casing, means positioned between said mounting member and casing to separate said recesses and having an aperture connecting upper portions of said recesses to provide an overflow opening, a discharge passage for the device, valve means for controlling the flow of fluid through said discharge passage, and means for diverting a portion of the fluid from the discharge passage to said second arcuate recess.

3. A device of the character described comprising, in combination, a unitary casing having a cylindrical recess in one end thereof, a shaft receiving bore extending through the other end thereof, a chamber for housing valve mechanism, an intake passage and a discharge passage, a detachable closure for the recessed end of the casing, a drive shaft rotatably mounted in said shaft receiving bore having one end extending into said cylindrical recess and the other end project-

ing from the casing, mechanical sealing means for the projecting end of said shaft, a rotary pumping means positioned in said cylindrical recess and removable therefrom as a unit comprising a mounting member secured detachably against the end wall of said recess and provided with a bore through which the shaft extends, an annular member positioned against said mounting member and forming the outer wall of a cylindrical pumping chamber, a plate member positioned against said annular member and cooperating with the mounting member and the annular member to form said cylindrical pumping chamber, a crescent-shaped guard secured to one of said members, a roller detachably splined to said shaft and positioned in said pumping chamber within said guard, an annular pumping member positioned in said pumping chamber externally of said guard, said pumping members having means to propel fluid through said chamber, means securing said plate member, said annular member and said mounting member together so as to be removable as a unit from the casing, a cup-shaped screen in said cylindrical recess intermediate said intake passage and the inlet to the pumping chamber and having its rim fitting snugly around said mounting member and against the end wall of said recess so as to be removable from the recess when said closure is detached, and valve mechanism in said valve chamber for controlling the flow of fluid through the discharge passage.

4. A device of the character described comprising, in combination, a unitary casing having a cylindrical recess in one end thereof, a shaft receiving bore extending through the other end thereof, a chamber for housing valve mechanism, and intake and discharge passages arranged at their outer ends for connection to external conduits, a detachable closure for the recessed end of the casing, a drive shaft rotatably mounted in said shaft receiving bore having one end extending into said cylindrical recess and the other end projecting from the casing for connection to a drive motor, mechanical sealing means for the projecting end of said shaft, a rotary pumping means positioned in said cylindrical recess, means for securing said pumping means detachably in the casing and in disconnection with said shaft so as to be removable therefrom as a unit when said closure is removed and without disturbing said conduit connections or the connection to a drive motor comprising a mounting member secured detachably against the end wall of said recess and provided with a bore through which the shaft extends, an annular member positioned against said mounting member and forming the outer wall of a cylindrical pumping chamber, a plate member positioned against said annular member and cooperating with the mounting member and the annular member to form said cylindrical pumping chamber, means including a member detachably splined to said shaft for propelling fluid through said pumping chamber, means securing said plate member, said annular member and said mounting member together so as to be removable as a unit from the casing, a cup-shaped screen in said cylindrical recess intermediate said intake passage and the inlet to the pumping chamber and having its rim fitting snugly around said mounting member and against the end wall of said recess so as to be removable from the recess when said closure is

detached, and valve mechanism in said valve chamber for controlling the flow of fluid through the discharge passage.

5. A device of the character described comprising, in combination, a unitary casing having a cylindrical recess in one end thereof, a shaft receiving bore extending through the other end thereof, a chamber for housing valve mechanism, and intake and discharge passages arranged at their outer ends for connection to external conduits, a detachable closure for the recessed end of the casing, a drive shaft rotatably mounted in said shaft receiving bore having one end extending into said cylindrical recess and the other end projecting from the casing for connection to a drive motor, a rotary pumping means positioned in said recess, means for securing said pumping means detachably in the casing and in disconnectible driven engagement 10 with said shaft so as to be removable therefrom as a unit when said closure is removed and without disturbing said conduit connections or the connection of the shaft to a drive motor comprising a mounting member secured detachably 15 against a wall of said recess and provided with a bore through which the shaft extends, an apertured member positioned against said mounting member and forming the outer wall of a pumping chamber, a plate member positioned against 20 said apertured member and cooperating with the mounting member to form the pumping chamber, means including a member detachably splined to said shaft for propelling fluid through said pumping chamber, means securing said plate 25 member, said apertured member and said mounting member together so as to be removable as a unit from the casing, a cup-shaped screen in said cylindrical recess intermediate said intake passage and the inlet to the pumping chamber 30 and having its rim fitting snugly around said mounting member so as to be removable from the recess when said closure is detached, and valve mechanism in said valve chamber for controlling the flow of fluid through the discharge passage. 35

6. A device of the character described comprising, in combination, a casing having a recess therein, a rotary pumping means positioned in said recess, including a mounting member detachably secured to one end wall of said recess, an intake port in said casing communicating with said recess, a recess in said mounting member in the face engaging the casing which communicates with said pumping means, a second recess in the adjacent wall of the casing, means positioned between said mounting member and casing to separate said last mentioned recesses and having an aperture connecting upper portions of said recesses to provide an overflow opening, a discharge passage for the device, valve means for controlling the flow of fluid through said discharge passage, and means for diverting a portion of the fluid from the discharge passage to said second recess.

7. A device of the character described comprising, in combination, a casing having a recess therein, a rotary pumping means positioned in said recess, including a mounting member detachably secured to one end wall of said recess, interengaging toothed members and a crescent guard between portions thereof, an intake port in said casing communicating with said recess, a recess in said mounting member in the face engaging the casing, means establishing communication between said last mentioned recess and said pumping members in the vicinity of said guard, a discharge passage for the device, valve means for controlling the flow of fluid through said discharge passage, and means for diverting a portion of the fluid from the discharge passage to said second mentioned recess.

8. A device of the character described comprising, in combination, a unitary casing having a recess in one end thereof, a shaft receiving bore extending through the other end thereof, a chamber for housing valve mechanism, and intake and

discharge passages arranged at their outer ends for connection to external conduits, a detachable closure for the recessed end of the casing, a drive shaft rotatably mounted in said shaft receiving bore having one end extending into said recess and the other end projecting from the casing for connection to a drive motor, a rotary pumping means positioned in said recess, means for securing said pumping means detachably in the casing and in disconnectible driven engagement 10 with said shaft so as to be removable therefrom as a unit when said closure is removed and without disturbing said conduit connections or the connection of the shaft to a drive motor comprising a mounting member secured detachably 15 against a wall of said recess and provided with a bore through which the shaft extends, an apertured member positioned against said mounting member and forming the outer wall of a pumping chamber, a plate member positioned against 20 said apertured member and cooperating with the mounting member to form the pumping chamber, means including a member detachably splined to said shaft for propelling fluid through said pumping chamber, means securing said plate 25 member, said apertured member and said mounting member together so as to be removable as a unit from the casing, a cup-shaped screen in said cylindrical recess intermediate said intake passage and the inlet to the pumping chamber 30 and having its rim fitting snugly around said mounting member so as to be removable from the recess when said closure is detached, and valve mechanism in said valve chamber for controlling the flow of fluid through the discharge passage. 35

9. A rotary pump comprising, in combination, a casing having a first and a second part, a recess in one of said parts, the other of said parts forming a removable closure, a rotary pumping means positioned in said recess comprising a 40 housing mounted on one of said parts and forming a pump chamber, interengaging toothed members positioned in said chamber and a crescent guard between portions thereof, said housing being provided with an intake port for the pump 45 chamber, means forming an auxiliary chamber in said part on which said housing is mounted, a discharge passage for the pumping means, a passage for conducting a portion of the liquid discharged from the pumping means to the auxiliary chamber, and an auxiliary intake port for the pumping means communicating with said toothed members in the vicinity of said guard and connected to receive fluid from said auxiliary chamber to compensate for any deficiency of 50 fluid in the spaces between the teeth of said members.

10. A device of the character described comprising, in combination, a casing having a first and a second part, one of said parts having a 60 recess in one end thereof, a shaft receiving bore extending through the other end thereof, a chamber for housing valve mechanism, intake and discharge passages provided in said casing and arranged at their outer ends for connection to external conduits, the other part forming a detachable closure for the recessed end of the first part, a drive shaft rotatably mounted in said shaft receiving bore having one end extending into said recess and the other end projecting from the casing for connection to a drive motor, mechanical sealing means for the projecting end of said shaft, a rotary pumping means provided with an inlet port and positioned in said recess, means for securing said 65

5 pumping means detachably to the inner end wall of one of said casing parts and in disconnectible driven engagement with said shaft so as to be removable therefrom as a unit when said closure is removed and without disturbing said conduit connections or the conection of the shaft to a drive motor, a screen in said recess intermediate

said intake passage and the inlet port to the pumping means and supported from said pumping means to be removable from the recess when said closure is detached, and valve mechanism in said valve chamber for controlling the flow of 5 fluid through the discharge passage.

GUNNAR A. WAHLMARK.
